UNITED STATES PATENT OFFICE.

WILLIAM T. SMITH, OF PHILADELPHIA, PENNSYLVANIA.

DESIGN FOR A CURTAIN.

SPECIFICATION forming part of Design No. 19,318, dated September 17, 1889.

Application filed May 13, 1889. Serial No. 310,649. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Curtain; and I do hereby declare that the photographic print accompanying this specification conveys to any one skilled in the art a clear understanding of the same, and is sufficient to enable such person to use my invention.

The leading feature of my design consists of a dado formed by the ornamental figures at A and cross-stripes B.

The body or top of the curtain has a plain

ground ornamented by shaded dashes D in two or more colors, as shown in the photographic print.

What I claim as my invention is—

1. The design for a curtain, the same comprising the ornamentations A, B, and D, as shown in the photographic print.
2. The design for a curtain top or body ornamented by shaded dashes D, in two or more colors, as shown in the photographic print.

W. T. SMITH.
